Primary Examiner — Katrina A Betton

CLAIM

The ornamental design for a car trunk organizer, as shown and described.

DESCRIPTION

FIG. 1 is a front, top perspective view of a car trunk organizer, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is an enlarged view of detail "9" identified in FIG.2; and,
FIG. 10 is another perspective view of the car trunk organizer, shown in an alternative position.
The dash dot dash lines in FIGS. 2 and 9 are for the purpose of illustrating the enlarged view indicators and form no part of the claimed design.
